UNITED STATES PATENT OFFICE

MARTIN O. HANEY, OF IOLA, KANSAS

DESIGN FOR A POTATO MASHER OR SIMILAR ARTICLE

Application filed July 9, 1932. Serial No. 44,292. Term of patent 7 years.

To all whom it may concern:

Be it known that I, MARTIN O. HANEY, a citizen of the United States, residing at Iola, in the county of Allen and State of Kansas, have invented a new, original, and ornamental Design for a Potato Masher or Similar Article, of which the following is a specification, reference being had to the accompanying drawing, forming part thereof.

I claim:—

The ornamental design for a potato masher or similar article as shown.

MARTIN O. HANEY.
